Wes. 1151

E. J. Bridge, of Troy, New York.
Letters Patent No. 1151. Dated Oct. 4, 1859.

The schedule referred to in these Letters Patent, and making part of the same.

To all whom it may concern:

Be it known that I, E. J. Bridge, of Troy, in the County of Rensselaer, and State of New York, have invented or produced a new and original design for a box stove, and that I do hereby declare that the following is a full clear and exact description of the same reference being had to the annexed drawings and letter of reference marked thereon, forming part of this specification, in which

Fig. 1. is a view of the side plate.

2

Ms. 115)

Fig: 2. a section of the same.

Fig: 3. is a view of the top plate.

Fig: 4. a section of the same.

The description of the plates is as follows: A, is the side plate, (a.a.) oval shell ornament, with oval perforations or panels (b.b) (d.d.) flat spaces separating reed mouldings (c.c.c) radiating from band or fillet (e.e) which encloses the plain oval figure (f.) forming the center of the design (g.g.) corner panels. B is the top plate. C is the moulding forming the border of the plate, the moulding is formed of (1.) ovolu member (2.) Scotia member (3.) ovolu member.

Having described my design for Stove plates,

What I claim as new therein and desire to secure by Letters Patent is; the ornamental design and configuration of Stove Plates such as herein described and shown in the annexed drawings.
